(57) **CLAIM**

The ornamental design for a sit and spin toy, as shown and described.

DESCRIPTION

FIG. 1 is a perspective view of the sit and spin toy showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a partial enlarged view of portion 9 in FIG. 1; and,

FIG. 10 is a partial enlarged view of portion 10 in FIG. 1. The dash-dash broken lines show portions of the sit and spin toy and form no part of the claimed design. The dash-dot broken lines show the bounds of the detail view and form no part of the claimed design.

1 Claim, 10 Drawing Sheets(56)
